SHEET METAL OVEN

Filed Oct. 11, 1922

2 Sheets-Sheet 2

UNITED STATES PATENT OFFICE.

HENRY KIELBERG, OF MARTINS FERRY, OHIO, ASSIGNOR TO WHITAKER-GLESSNER COMPANY, OF WHEELING, WEST VIRGINIA, A CORPORATION OF WEST VIRGINIA.

SHEET-METAL OVEN.

Application filed October 11, 1922. Serial No. 593,805.

To all whom it may concern:

Be it known that I, HENRY KIELBERG, a citizen of the United States of America, and resident of Martins Ferry, county of Belmont, and State of Ohio, have invented certain new and useful Improvements in Sheet-Metal Ovens, of which the following is a specification.

This invention relates broadly to sheet metal ovens, and more specifically to an oven of the portable type designed for mounting upon stoves, hot plates and the like.

The primary object of the invention is to provide a portable sheet metal oven of knock-down form composed of parts which may be quickly and conveniently set up and knocked down as occasion requires, which is strong, rigid and substantial when said parts are properly assembled, and which when knocked down may be conveniently packed in relatively small compass either for storage purposes or for shipment.

With these and other objects in view the invention resides in the features of construction, arrangement of parts and combinations of elements which will hereinafter be fully described, reference being had to the accompanying drawings, in which—

Figure 1 is a front elevation of the invention with its parts fully assembled;

Figure 2 is an end elevation of the same; Figure 3 is a section on line 3—3, of Fig. 1, showing the oven door in open position;

Figure 4 is an upper edge view of the oven casing in its collapsed form;

Figure 5 is a partial horizontal section on line 5—5, Fig. 2;

Figure 6 is an enlarged fragmentary section taken on line 6—6, Fig. 3; and—

Figure 7 is an enlarged fragmentary section taken substantially on line 7—7, Fig. 2.

Referring to said drawings, 1 indicates the front wall and 2 the rear wall of a collapsible sheet-metal casing which, in its extended form, is rectangular in shape. Said front wall 1 has each of its opposite ends turned rearward at a right angle to the plane of said wall, forming end portions 1^a having substantial width. Likewise, end portions 2^a are formed by turning the ends of the rear wall 2 forward at right angles to the plane of said wall. A panel 3 of rectangular form interposed between the adjacent end

portions 1^a and 2^a complements said portions in forming the ends of said casing, said panel being hinged at its front and rear vertical edges to said portions 1^a and 2^a, respectively, as shown at 4 and 5. Due to this hinged arrangement of the ends, the casing is rendered foldable to and from approximately the collapsed form shown in Fig. 3 of the drawings.

The lower edges of the walls 1 and 2 are provided with narrow inturned flanges 1^b and 2^b, respectively, and the lower edges of the end panels are likewise turned inward to form flanges 3^b. Said flanges serve not only as foot portions upon which the casing stands, but also as supports for the edges of a rectangular bottom 6 which is insertible and removable through the top of said casing and which, when seated upon said flanges serves effectively to brace the lower part of the casing. Said bottom has therein one or more large central openings 7 defined by an encircling stiffening flange 8, said opening or openings being adapted to permit heat and flame to unobstructedly enter the interior of the casing from the burners of a stove (not shown) upon which the casing is seated when in use.

Removably disposed against the inner face of the rear casing wall 2 is a sheet-metal plate or shield 9, preferably corrugated for stiffening purposes, whereby said rear wall is protected from the heat, said shield having its lower edge resting upon the bottom 6. The opposite ends of said shield are turned forward and thence inward into hook-like form to provide channels 10. Received in said channels are outwardly turned flanges 11^a formed on the rear vertical edges of plates 11 which serve to shield the end walls of the casing from heat, said shields 11 also being preferably corrugated. The front edges of said shields 11 have outturned flanges 11^b which seat against the end portions 1^a closely adjacent to the angles between said portions and the front wall 1, as shown in Fig. 5.

A door 12 hinged at its lower edge to the wall 1 is normally disposed in upright closing relation to an opening 13 provided in said wall and through which access is had to the interior of the oven for the introduction and removal of cooking vessels, baking pans, and the like. Said door open-

ing is made of sufficient width to permit the passage therethrough to and from seated position of wire racks 14 adapted to support thereon vessels and pans. Said racks are 5 designed to slide to and from positions in which their ends rest upon seating ledges 15 provided at intervals on the end shields 11, said ledges being pressed in the metal of said shields.

10 The door 12 may be held in its upright closed position by any suitable means, as by bar-like latch members 16 which are movable into and out of locking relation to the interior face of the portion of the front wall 15 located directly over the door opening 13, said members 16 being carried by the stem portions of rotatable door-handles 17. Pivotally attached to the opposite lateral edge portions of the door are members 18 by 20 which said door is firmly supported in its horizontal open position to form a shelf-like support. Each of said members consists of a wire shaped to form an arcuately curved body and outer and inner end terminals 18^a and 18^b, respectively, the terminal 18^a being pivotally mounted in a loop-like keeper 19 formed on the door. The curved body of said member extends through a hole 20 provided therefor in the wall 1 adjacent to the 30 door and is movable through said hole in opening and closing movements of the door. The inner terminal 18^b is down-turned and is movable to and from seated relation to the wall 1 through a cut-out portion or recess 21 provided therefor in the adjacent flange 11^b of the adjacent end shield 11.

40 Mounted upon the top of the casing is a cover, generally designated by the reference character 22 by means of which the upper end of the casing walls are held in rigidly braced relation. Said cover comprises a top plate 22^a having suitably attached to the under side thereof a downwardly dished shield plate 22^b which has a size and form for fitting closely within the embrace of said casing walls, as shown in Figs. 3 and 7. Said cover is held in closely seated position by spring fingers 23 which depend from the under side of the cover and which are adapted to be sprung into and out of apertures 24 provided therefor in the end panels 3. The said cover and the attaching means therefor constitute the subject matter of a companion application, Serial No. 593,806, to which 55 reference is herein made for a complete description.

60 The lowermost rack 14 embodies means whereby heat and flame from the underlying stove are prevented from coming into direct contact with pans or vessels mounted thereon, the specific structure involved being disclosed in a companion application, Serial No. 593,807, to which reference may be had for a description thereof.

65 The oven described is designed to be

packed for shipment and for storage in knocked-down form, the casing being collapsed into substantially the form shown in Fig. 4, and the parts consisting of the bottom 6, shield plates 9 and 11, racks 14, and cover 22 being together introduced within the embrace of said collapsed casing.

What is claimed is—

1. A knock-down oven comprising a rectangular casing having the walls thereof in collapsible hinged relation, the front wall of said casing having a doorway therein, a bottom removably mounted within the lower part of said casing in bracing relation to the walls of the latter, shield plates removably mounted adjacent to the rear and end walls of said casing, said end shield plates being disposed in bracing relation to said rear shield plate, racks removably mounted within said casing and bracing said end shield plates, and a cover detachably mounted upon the top of said casing in bracing relation to the walls of the latter. 75

2. A knock-down oven comprising a rectangular casing having the walls thereof in collapsible hinged relation, the front wall of said casing having a doorway therein, said casing walls having inwardly directed flanges at their lower edges, a bottom seated upon said flanges in bracing relation to the casing walls, said bottom being insertible through the interior of said casing from the top of the latter, shield plates removably mounted adjacent to the rear and end walls of said casing and slidable vertically to and from seated relation to said bottom, said end shield plates being interengaged with and bracing said rear shield plate, racks slidable horizontally into and out of supported bracing relation to said end shield plates, and a cover detachably seated upon said casing in bracing relation to the walls of the latter. 90

3. A knock-down oven comprising a rectangular casing having the walls thereof in collapsible hinged relation, means removably mounted within the lower part of said casing for bracing said casing walls, shield plates removably mounted within said casing adjacent to the end walls of the latter, means for bracing said plates in upright position, said plates having flanges whereby they are maintained at a spaced distance from said end walls, the front casing wall having a door opening therein, a door hinged to said front wall and movable to and from closing relation to said opening, arcuately curved members attached to the door for limiting the extent of opening movement of said door and whereby the latter is supported when open, said members being movable through the front casing wall adjacent to the end walls of the casing and having terminals for seating against said front wall, the foremost flanges of said shield plates being 105 recessed to permit passage of said terminals, 110

115

130

and a cover detachably seated upon said casing in bracing relation to the walls of the latter.

4. A knock-down oven comprising a rectangular casing having the walls thereof in collapsible hinged relation, a bottom removably mounted within the lower part of said casing for bracing said casing walls, shield plates removably mounted within said casing adjacent to the end walls of the latter, said plates having ledges formed thereon, racks slideable to and from seated relation to said ledges and whereby said plates are braced, and a cover detachably seated upon said casing in bracing relation to the walls of the latter.

5. A knock-down oven comprising a rectangular casing having the walls thereof in collapsible hinged relation, means remov-

ably mounted within the lower part of said casing for bracing said casing walls, shield plates removably mounted within said casing adjacent to the end walls of the latter, a shield plate removably mounted adjacent to the rear wall of said casing and abutted and braced in place by said end plates, said end plates having ledges formed thereon, racks slideable to and from seated relation to said ledges and whereby said end plates are braced, and a cover detachably seated upon said casing in bracing relation to the walls of the latter.

In testimony whereof, I affix my signature in presence of two subscribing witnesses.

HENRY KIELBERG.
